UNITED STATES PATENT OFFICE.

ELIAS B. BALDWIN AND EFFENGER R. KLINE, OF SAYRE, PENNSYLVANIA.

SPARK-ARRESTER.

SPECIFICATION forming part of Letters Patent No. 300,555, dated June 17, 1884.

Application filed January 14, 1884. (No model.)

To all whom it may concern:

Be it known that we, ELIAS B. BALDWIN and EFFENGER R. KLINE, both of Sayre, in the county of Bradford and State of Pennsylvania, have invented a new and Improved 5 Spark-Arrester, of which the following is a full, clear, and exact description.

The object of our invention is to provide a new and improved device for arresting the 10 sparks and cinders in locomotives and prevent their being ejected out of the smoke-stack.

The invention consists in the combination, 15 with the smoke-box, of an outlet-pipe extending downward and backward, and of means for conveying the cinders into the upper end of the outlet-pipe.

The invention further consists in the combination, with the above devices, of a winged 20 wheel mounted on a shaft held in front of the outlet ends of the exhaust-pipes, whereby the said wheel can be operated by the exhaust-steam.

Reference is to be had to the accompanying 25 drawings, forming part of this specification, in which similar letters of reference indicate corresponding parts in all the figures.

Figure 1 is a front view of our improved 30 spark-arrester. Fig. 2 is a longitudinal sectional elevation of the same. Fig. 3 is an end view of the fan-wheel.

In the smoke box or compartment A, at the front end of the boiler B, on which box the smoke-stack is fastened, two standards, C, are 35 secured, in the upper ends of which a shaft, D, is journaled transversely across the front of the boiler. On the said shaft D a winged or bucket wheel, E, is mounted, which is placed in front of the horizontally-bent upper ends 40 of the steam-exhaust pipes H. On the shaft D a pulley, J, is mounted, over which a belt or chain, K, passes, which also passes over a smaller pulley, L, on a shaft, M, journaled in the lower parts of the standards C and parallel with the shaft D. A fan-wheel, N, is mounted on the shaft M, and in front of the fan-wheel N the upper end of a pipe, O, is located, which pipe extends out of the front of the compartment A, and is bent downward and backward 45 between the wheels of the locomotive, as shown in Fig. 2. The lower end of the pipe O is closed by a gate or valve, P, which can be opened or closed from the locomotive-cab by

means of a rod or rope, Q. The steam escaping through the exhaust-pipes H revolves the 55 wheel E and the shaft D, and from the shaft D the fan-wheel N is revolved and throws the cinders that accumulate on the bottom of the box or compartment A into the pipe O. At suitable intervals the valve or gate P is opened 60 to let the cinders slide out of the bottom of the pipe O.

If desired, the shaft M can be revolved from one of the axles of the locomotive.

If desired, conveyer-screws can be used in 65 place of the fan-wheel to carry the cinders into the upper end of the pipe O.

Having thus described our invention, we claim as new and desire to secure by Letters Patent—

1. In a spark-arrester, the combination, with the exhaust-pipes, of a winged wheel in front of the upper ends of the exhaust-pipes, and a fan-wheel for throwing the cinders into an outlet-pipe operated by the said winged wheel, 75 substantially as herein shown and described.

2. In a spark-arrester, the combination, with the smoke-box A, of the pipe O, extending downward and backward from the bottom part of the smoke-box, and of means, substantially 80 as described, for conveying the cinders into the upper end of the pipe O, substantially as herein shown and described.

3. In a spark-arrester, the combination, with the smoke-box A, of the pipe O, extending 85 downward and outward from the bottom part of the said box, means, substantially as described, for conveying the cinders into the upper end of the pipe O, and of the gate or valve P, for closing the lower end of the pipe 90 O, substantially as herein shown and described.

4. In a spark-arrester, the combination, with the standards C in the smoke-box, of the shaft D, journaled in the upper ends of the standards C, the winged wheel E, and the pulley J, mounted on the shaft D, the exhaust-pipes H, the shaft M, the fan-wheel N on the same, the pulley L, the belt K, and the outlet-pipe O, substantially as herein shown and described.

ELIAS B. BALDWIN.
EFFENGER R. KLINE.
